Specification of Letters Patent.

Patented May 7, 1918.

Application filed May 22, 1915. Serial No. 29,790.

To all whom it may concern:

Be it known that we, FRANK W. HOWARD and GEORGE B. CANNON, Jr., both citizens of the United States, said FRANK W. HOWARD residing at New York city, in the county of New York and State of New York, and whose post-office address is 9 Fort Washington avenue, New York city, New York, said GEORGE B. CANNON, Jr., residing at Brooklyn, in the county of Kings and State of New York, and whose post-office address is 154 Rogers avenue, Brooklyn, New York, have invented new and useful Improvements in Umbrellas, of which the following is a specification.

This invention relates to umbrellas. A principal object of the invention is to produce an umbrella which can be very economically manufactured, the idea being that the umbrellas may be kept on sale in frequented places to be bought by persons who are unexpectedly caught in the rain.

One of the objects of the invention is to produce an umbrella having a cover applied to the ribs by such means as will reduce the strains exerted by the frame on the cover of the umbrella to a minimum, and particularly adapting the umbrella to be constructed with relatively frangible non-extensible material such as water-proof paper.

A further object of the invention is to produce such an umbrella in which the connections of the cover with the crown and the ribs at all points are such as will tend to prevent tearing of the paper out of which the cover is formed.

A further object of the invention is to produce a paper covered umbrella having a frame very similar to that of an ordinary cloth covered umbrella, and enabling the umbrella to be rolled up so as to present substantially the appearance of an ordinary cloth covered umbrella.

Further objects of the invention will appear more clearly hereinafter.

The invention consists in the general combination of parts and details hereinafter described, all of which contribute to produce an efficient umbrella.

The preferred embodiment of our invention will be particularly described in the following specification, while the broad

scope of our invention will be pointed out in the appended claims.

In the drawings,

Figure 1 is a vertical section through an open umbrella, embodying our invention, a portion of the stick being shown in cross section.

Fig. 1^a is a vertical section taken through the crown of the umbrella showing the adjacent portions of the stick, cover and ribs broken away.

Fig. 2 is a side elevation showing the umbrella rolled and creased.

Fig. 3 is a plan showing a portion of the edge of the umbrella and further illustrating details of its construction.

Fig. 4 is a plan of a blank or cover section out of which the cover is preferably formed.

Fig. 5 is a cross section illustrating the manner in which the cover sections are attached together to form the complete cover. This view is upon an enlarged scale.

Fig. 6 is a plan showing a portion of the edge of the cover along the seam or line of attachment of two cover sections and illustrating details of the construction at this point. This view illustrates a preferred manner of attaching eyelets at the edge of the umbrella for securing the umbrella to the ends of the ribs.

Fig. 7 is a view similar to Fig. 6 but illustrating the parts before the eyelet is attached.

Fig. 8 is a plan illustrating the parts with the seam at right angles to the plane in which the cover is supposed to lie.

Fig. 9 is a perspective illustrating the manner in which the connecting seam between two sections is formed preparatory to producing the effect illustrated in Fig. 6.

Fig. 10 is a section upon an enlarged scale taken on the line 10—10 of Fig. 6 and illustrating one effect of the construction which is to produce an overlap comprising a great number of plies or layers of material through which the eyelet passes.

Fig. 11 is a cross section taken on the line 11—11 of Fig. 6 and illustrating the manner in which the seam lies against the inner side of the umbrella cover.

Fig. 12 is a plan showing a portion of the cover at a connecting seam between two sec-

tions and illustrating the manner in which the rib lies along the seam. This view illustrates one means for holding the rib on the seam.

5 Fig. 13 is a section taken on the line 13—13 of Fig. 12.

Fig. 14 is a vertical section taken on the broken line 14—14 and particularly illustrating the construction at the edge of the 10 cover and at the point where the cover is attached to the ribs.

Fig. 15 is a plan showing a fragment of the seam between two cover sections, and illustrating another means for holding the 15 umbrella rib on the seam.

Fig. 16 is a cross section taken on the line 16—16 of Fig. 15.

Fig. 17 is a view similar to Fig. 16 but showing a modified arrangement of the 20 parts.

Before proceeding to a detailed description of the invention, it should be stated that we are well aware that parasols have been constructed of paper, but the frames of such 25 parasols including the ribs have usually been made of strips of wood to which the paper was attached by an adhesive. This construction is not adapted for producing a compact, tightly rolled umbrella such as may 30 be produced according to our invention.

It is not feasible to secure a paper cover to an ordinary steel umbrella frame in the same manner that a cloth cover would be attached, because there is a tendency to 35 produce a concentration of strain at a number of points which could not be withstood by a water-proof paper which may be torn with comparative ease. These points of strain are located principally at the crown 40 of the umbrella where the cover is attached to it, at the edges of the umbrella where it is attached to the ribs, and along the length of the ribs where they press against the inner side of the stretched cover.

45 We will now describe an embodiment of our invention involving the special construction of the umbrella at the points referred to, particularly adapting the umbrella to employ a paper cover.

50 Referring more particularly to the parts, 20 indicates the umbrella stick which is preferably formed of wood, and which may have a round knob 21 to form a handle.

The features of the construction at the 55 crown 22 of the umbrella are preferably such as were disclosed in the pending application, Serial No. 859,067.

The umbrella frame preferably comprises 60 ribs 23 of light steel or similar resilient metal, and these ribs have reduced inner ends or integral flattened extensions 24 which are secured against the side of the umbrella "stick" by means of a crown sleeve 25 which clamps the extensions rigidly 65 against the stick. When the "stick" is of

a yielding material such as wood, the sleeve may be so tight as to force the extensions 24 into the side of the "stick," and thus secure them against lateral movement on the stick. This construction is illustrated in 70 Fig. 1^a in which, however, the sleeve 25 is not represented with cross section lines, although it is actually in section. These lines are omitted for the sake of clearness. The ribs 23 flex outwardly at the 75 points 26 of the flat or flattened extensions just below the lower end of the sleeve 25, which lower end is preferably formed with an outwardly flared mouth or lip 27. This prevents the formation of a sharp edge at 80 which the ribs might bend and break. In order to prevent any tendency of the extensions 24 to move longitudinally on the stick after the clamping sleeve 25 has been put in place, we prefer to form slight notches 85 or recesses 28 in the outer faces of the extensions 24, and then after the sleeve has been put in place, we offset the material inwardly slightly to form a projection or spur 29, projecting into the recess. This 90 evidently will hold the extension against sliding.

The cover 30 is preferably formed of a plurality of cover sections 31 of substantial triangular form, (see Fig. 4). The side 95 edges 31^a of these cover sections present long convex curves 32 which form an ogee curve with concave lines 33 at the small end of the cover section. A plurality of the cover section 31 are then attached together along 100 their side edges and this is preferably accomplished by sewing. In order to adapt the paper for sewing, we prefer to moisten it which has the effect of giving the paper greater flexibility and enabling it to be 105 worked with a sewing machine in much the same way as cloth.

These cover sections 31 are then attached together at their side edges 31^a by means of seams, such as the seam 34 (see Figs. 5 111 and 9). At the outer edge 35 each cover section, however, is folded over upon itself 111 so as to form an outer edge seam 36 for the umbrella, and if desired, to give the umbrella great strength, we prefer to secure in the seam 36 gussets 37 of cloth or similar material, and these gussets are disposed at the corners of the cover sections 31 so that when the sections are attached together, one of the seams at the edge of the 112 umbrella will present substantially the appearance shown in Fig. 9. At the point where the small ends 38 of the cover sections are attached, of course, a small opening is produced which is at the center of the cover. 113

The umbrella cover is then turned wrong side out and the edge 39 of the cover at the center opening is secured to the sleeve 25, preferably by means of a cord 40 which is tied around the sleeve just above the en- 114

larged mouth or lip 27. The umbrella cover is then turned right side out so that it may hang down from the stick and sleeve in the manner indicated in Fig. 1^a. In attaching 5 the cover to the sleeve, it is preferable that the edge 39 should project beyond the edge of the lip 27 because this arrangement reduces the strain of the lip on the cover at this point. The upper edge or center of the 10 cover is then preferably concealed by means of an outer sleeve 41 which is forced on to the stick, said sleeve preferably having an outwardly expanded mouth 42 for this purpose.

15 The umbrella preferably includes a runner 41^a of any suitable construction which slides on the stick 20 and which is connected by stretchers 43 with intermediate points on the ribs 23. After the seams 34 are formed, 20 they are then turned over or laid flat upon the inner side of the cover, and when this is done, the outer end of the seam will present a projecting end 44. This end is then folded back over the edge of the cover so as 25 to fold an overlap 45 (see Fig. 6), said overlap being formed on the seam 34. Through each of these overlaps we attach an eyelet 46 which passes completely through the overlap and the cover. When 30 the cover 30 is applied to the ribs, the end of each rib is then bent outwardly so as to form an eye 47 which eye engages with the eyelet 46 and secures the cover to the rib (see Fig. 14).

35 The full length of each rib is then disposed along the inside of the cover at each of the seams 34 and each seam 34 which presents two layers of the material lies against the inner side of the cover. These seams 40 being of two thicknesses of the paper and also being of stiff material distribute the pressure of the rib on the cover. In order to prevent any possibility of the ribs working laterally so as to become displaced from the 45 seams, we prefer to provide guiding means for holding each rib in position, but this guiding means preferably does not prevent the free longitudinal movement of the rib through the guide and hence it does not interfere in any way with the opening and 50 closing of the umbrella nor does it tend to produce any unequal stretching of the material of the cover at different points. This guiding means may be such as that illustrated in Fig. 12 or such as that illustrated 55 in Fig. 15. In the embodiment shown in Figs. 12 and 13, the guiding means comprises an eyelet 48 having an integral tongue which is bent to form a resilient spring hook 60 49. The rib may be engaged with this hook by a lateral movement of the rib and the resiliency of the hook will tend to keep the guide means in engagement with the rib.

55 A reinforcing piece 34^a of stiff paper is preferably sewed onto the seams 34 to

strengthen the hold of the eyelet. We may, however, employ the guide means 50 illustrated in Figs. 15 and 16 which consists of a flat loop of paper or similar material, one edge 51 of the loop being attached on one side of the seam and the other edge 52 being attached on the other side of the seam. The rib passes between one side of the loop and the seam (see Fig. 16). If desired, however, the loop may not encircle the seam but may 70 be applied to the side of the seam (see Fig. 17) where 53 indicates the flat loop, the edges of which are attached at 54 to the seam. In this form of guide the loops may be attached readily by means of the stitching or sewing 55 which attaches the laps of the seam together.

75 When the gussets 37 are employed, it is evident that forming the overlap 45 as described, produces a greatly increased number of thicknesses of material through which the eyelet 46 passes (see Fig. 10). This arrangement gives the eyelet a very secure hold on the edge of the cover and distributes the strains in all directions, and this effect is 80 augmented by the gussets.

85 In order to insure that the seams 34 will have the effect of distributing the pressure of the rib on the cover, it is preferable to make the seams 34 relatively very wide (see 90 Fig. 3).

95 When an umbrella is constructed as described with a paper cover, it may be closed like an ordinary cloth covered umbrella, and then rolled up tightly in the manner indicated in Fig. 2, the creases 56 being formed midway between the location of the ribs. We provide means for encircling the rolled umbrella which is variable in its encircling 100 length in order to insure that no undue strain will be put upon its anchorage in the cover; for this purpose, near one of these creases a fastener or tie is provided, preferably in the form of a cord 57, one end of the cord being anchored on a button 58. 105 When the umbrella is rolled up, the end of this cord is given a few turns around the button so as to hold the umbrella rolled. Evidently this can be done so as to hold the umbrella neatly rolled but without subjecting 110 the fastener to great strain.

115 An umbrella having the features of construction described above may be very economically manufactured and is so constructed as to distribute the strains to which the 120 cover is subjected by the frame when held open in the wind and rain. In order to facilitate the umbrella being rolled up tightly in the manner indicated in Fig. 2, it is advisable to moisten the umbrella cover, particularly in the vicinity of the crown in order to prevent the tendency of the cover to tear at this point. If the umbrella cover is moistened as suggested, it can be neatly rolled, and when the umbrella cover is 125 130

formed of black paper, the rolled umbrella will present substantially the same appearance as an ordinary cloth covered umbrella.

As indicated in Fig. 2, when the umbrella is folded, the runner is exposed on the stick beyond the edge of the cover. This enables the umbrella to be rolled more compactly than otherwise, and also leaves the runner exposed so that it can be readily seized when the umbrella is to be opened.

It is understood that the embodiment of the invention set forth herein is only one of the many embodiments or forms the invention may take, and we do not wish to be limited in the practice of the invention nor in our claims to the particular embodiment set forth.

In the open umbrella evidently the radial pull of the eyelet is exerted through both the layers of the seam 34 as well as the outer part of the cover.

What we claim is:

1. An umbrella comprising a stick, a crown sleeve attached to said stick, an umbrella cover having a central opening attached to said sleeve, said cover consisting of a plurality of substantially triangular cover sections of water-proof paper, said sections having superposed edges sewed together to form a plurality of seams composed of layers, said seams extending radially on the cover from said stick and lying against said ribs, eyelets passing through the edge of said cover at said seams for attaching the outer edges of the cover to said ribs, said eyelets lying in the plane of the adjacent portion of the cover and lying with their flat sides against the outer sides of the ribs, and means on the ribs for engaging said eyelets to retain the same adjacent the ends of the ribs.

2. An umbrella comprising a stick, a crown sleeve attached to said stick, said crown sleeve having an outwardly turned lip at the lower end thereof, an umbrella cover having a central opening at said sleeve with the edge of said opening attached to the side of said sleeve above said lip so as to be retained by said lip, a plurality of ribs having flattened extensions lying against the side of said stick and secured thereto by said sleeve, said flattened extensions constructed to flex outwardly and permit the ribs at the lower end of said sleeve to move away from the stick in the direction of said lip to open the umbrella, said cover consisting of a plurality of substantially triangular sections of water-proof paper sewed together, and eyelets in the edges of the said cover, said ribs having outwardly turned ends forming eyes engaging said eyelets.

3. An umbrella comprising a stick, ribs extending therefrom, and a cover formed of substantially triangular sections of water-proof paper, said sections having superposed edges sewed together to form a plu-

rality of seams composed of layers of the paper, said seams extending radially on the cover from the stick and lying adjacent said ribs, the ends of said seams folded in upon the edge of said cover and thereby producing overlaps of an increased number of layers of said paper, and eyelets secured in said overlaps at the edges of said cover and engaging the ends of said ribs.

4. An umbrella comprising a stick, a crown sleeve attached to said stick, an umbrella cover having a central opening attached to said sleeve, said cover consisting of a plurality of substantially triangular sections of water-proof paper, said sections having superposed edges attached together to form a plurality of seams composed of two layers of the paper, reinforcing gussets at the corners of said cover sections, said seams extending radially upon the cover from said stick and lying against said ribs to distribute the pressure of the ribs upon the cover, and eyelets at the edge of said cover corresponding to said ribs, passing through said seams and said gussets, said ribs having outwardly bent ends forming eyes engaging said eyelets.

5. An umbrella comprising a stick, a crown sleeve attached to said stick, an umbrella cover having a central opening attached at said sleeve, a plurality of ribs attached to said stick at said sleeve, said cover consisting of a plurality of substantially triangular sections of water-proof paper sewed together at their side edges, said cover having overlaps at the edges thereof producing an increased number of layers of said paper, eyelets passing through said cover at said overlaps, said ribs having outwardly turned ends forming eyes engaging said eyelets.

6. An umbrella comprising a stick, a crown sleeve attached to said stick, an umbrella cover having a central opening attached at said sleeve, a plurality of ribs attached to said stick at said sleeve, said cover consisting of a plurality of substantially triangular sections of water-proof paper sewed together at their side edges, said cover having overlaps at the edges thereof producing an increased number of layers of said paper, eyelets passing through said cover at said overlaps, said ribs having outwardly turned ends forming eyes engaging said eyelets, and means on said cover at an intermediate point on each rib for guiding the ribs on the cover and permitting a free longitudinal movement of the ribs on the cover at said guiding means.

7. An umbrella comprising a stick, a crown sleeve on said stick, a plurality of ribs having flat extensions lying against the side of said stick and clamped against said stick by said sleeve, said extensions having recesses formed in the outer faces thereof, and said sleeve having an offset portion engaging

said recesses and preventing said extensions from moving longitudinally with respect to the sleeve.

8. An umbrella comprising a stick, a crown sleeve on said stick, a plurality of ribs having flat extensions lying against the side of said stick and clamped against said stick by said sleeve, said extensions having recesses formed in the outer faces thereof, and said sleeve having an offset portion engaging said recesses and preventing said extensions from moving longitudinally with respect to the sleeve.

9. In an umbrella, the combination of a stick, a plurality of ribs having integral flexible extensions extending longitudinally and lying against the sides of said stick, and constructed to flex at the point of connection with said stick to permit the opening and closing of the umbrella, and a sleeve fitting tightly over said extensions and forcing the same into said stick to secure said

extensions to said stick and prevent movement of said extensions relatively to the stick.

10. In an umbrella, the combination of a wooden stick, a plurality of ribs having integral flattened flexible extensions extending longitudinally of and lying against the sides of said stick, and constructed to flex to permit the opening and closing of the umbrella, and a sleeve fitting tightly over said extensions, forcing the said extensions into the wood of the stick and thereby securing the same to said stick.

In testimony whereof we have hereunto set our hands in presence of two subscribing witnesses.
